Primary Examiner — Sheryl Lane*Assistant Examiner* — Calvin E Vansant(74) *Attorney, Agent, or Firm* — Staniford Tomita LLP(57) **CLAIM**

What is claimed is the ornamental design for a micro fluidic chip, as shown and described.

DESCRIPTION

FIG. 1 is a perspective view of a micro fluidic chip;
FIG. 2 is a top view of a micro fluidic chip;
FIG. 3 is a front view of a micro fluidic chip;
FIG. 4 is a bottom view of a micro fluidic chip; and,
FIG. 5 is a side view of a micro fluidic chip.
In the drawings, the broken lines depict portions of the micro fluidic chip that form no part of the claimed design.
